UNITED STATES PATENT OFFICE.

WILLIAM LESLIE WILSON, OF HINTON, WEST VIRGINIA.

BY-PASS VALVE

No. 852,008.

Specification of Letters Patent.

Patented April 30, 1907.

Application filed May 19, 1906. Serial No. 317,832.

To all whom it may concern:

Be it known that I, WILLIAM LESLIE WILSON, a citizen of the United States, residing at Hinton, in the County of Summers and State of West Virginia, have invented a new and useful By-Pass Valve, of which the following is a specification.

This invention has relation to by-pass valves and it consists in the novel construction and arrangement of its parts as hereinafter shown and described.

The object of the invention is to provide a by-pass valve especially adapted to be used upon the steam cylinders or steam chests of a locomotive and is so constructed as to equalize the pressure on both sides of the piston head while the steam is cut off and the engine is moving and the pistons are reciprocating, thus permitting the locomotive to drift without creating a vacuum in the steam chest or cylinder. With such a mechanism a great saving is effected and wear and tear on the packings and mechanism is prevented.

The object of the present invention is to provide a valve adapted to be used as above indicated, said valve being of such construction as to prevent slamming of the valve and damage incidental thereto, should the pressure on each side of the valve become equalized, or when the valve is subjected to sudden changes of pressure. The valves are placed at each end of the cylinder and the valve casings communicate at one end with the live steam passage and at the other end with the exhaust passage. The stem of the valve extends in a lateral direction along the transverse axis on each side of the valve. And beyond the ends of the said stem dash pots are arranged in the valve casing. Each end of the stem is provided with a piston which is adapted to reciprocate in its adjacent dash pot and each piston is provided with ports which when their ends are uncovered, permit the pressure to enter the dash pot and operate against the under sides of the said valve stem pistons.

In the accompanying drawings: Figure 1 is a vertical sectional view of a cylinder and piston valve casing having the by-pass valve attached thereto, Fig. 2 is a horizontal sectional view of the by-pass valve, Fig. 3 is a vertical sectional view of one form of the by-pass valve, and Fig. 4 is a vertical sectional view of a modified form of the by-pass valve.

The drawing shows but one cylinder casing of a locomotive of the ordinary piston

valve type. The cylinder casting on the opposite side of the head is a duplicate of the one shown.

The cylinder casting 1 is provided with the cylinder 2 and the valve chamber 3, a steam inlet passage 4 and passages 5, 5, one communicating with one end of the cylinder and the other with the opposite end and 6 is the exhaust passage communicating with the ports at each end of the valve casing.

In the drawing the piston and its rod as well as the piston valve are omitted as these parts form no part of my invention and are of the construction ordinarily used in this type of engine.

Steam is admitted from the boiler through the central live steam passage 4 to a passage 5 and into one end of the cylinder while the steam is exhausting from the opposite end of the cylinder through the other passage 5 to the exhaust passage 6 and when the valve is moved in the opposite direction, the passage of the steam and exhaust are reversed.

Upon the piston valve casing the by-pass valve casings 7, 7 are located. The casings 7 communicate with the cylinder ports and with the live steam space. It is understood that a valve casing 7 is located one at each end of the piston valve casing. By reference to Figs. 2, 3 and 4 of the drawing, the construction of the by-pass valve may be understood. Within the casing 7 is arranged the partition 8 which is provided with an opening 9 ground at its edge to form a valve seat 10. Said partition 8 extends at an angle of about 45 degrees to a perpendicular erected from the point of attachment between the said casing 7 and its support. The valve 11 is adapted to seat against the valve seat 10. Said valve is provided on each side and along its central axis with the stems 12 and 13. The casing 7 is provided at one side with a recess 14 which is located directly opposite the opening 9 of the partition 8 and which constitutes a dash pot. The opposite side of the casing 7 is provided with a removable plate 15 which on its under side is provided with a recess 16 which also constitutes a dash pot and is located directly opposite the opening 9 of the partition 8 but on the opposite side thereof from the dash pot 14.

The extreme ends of the stems 12 and 13 are provided with the pistons 17 and 18 respectively. The piston 17 is adapted to reciprocate in the dash pot 14 and the piston 18 is adapted to reciprocate in the dash pot

16. The said pistons 17 and 18 are provided with the laterally extending ports 19 which open at their ends in the side of the piston and communicate with the central longitudinally extending port 20. The end of the port 20 is in the center of the face of its respective piston. The ports 19 are located substantially about half way between the opposite faces of the piston.
10. By reference to Figs. 3 and 4 it will be observed that the longitudinal central axis of the valve stems 12 and 13 are alined and that they extend at right angles to the partition 8 and consequently they are inclined at an angle of approximately 45 degrees to a perpendicular.
15. In the form of the casing 7 as shown in Fig. 4, the by-pass valve is adapted to be applied to the inclined side of a steam chest while in the form of the invention as shown in Fig. 3, the said casing is formed in order that the valve may be applied to the top of the steam chest although the said casings may be applied at any point between the live steam passage and the cylinder passage as in some types of engine it may not be convenient to place the valves in the position shown in the drawings. It will also be understood that while I have shown a locomotive with a central steam supply passage and end exhaust passages, this invention can be applied to an engine having end steam passages and a central exhaust without departing from the spirit of the invention.
20. It will thus be seen that when live steam enters the passage 5, that the pressure will pass up the end 21 of the casing 7 and lift the valve 11 and seat the same against the seat 10, thus closing the opening 9 of the partition 8. Thus when the steam is on, both of the by-pass valves are closed. When the steam is cut off from the cylinder and the engine is in motion, the valves 11 will fall away from the seats 10 and thus both ends of the cylinder 2 are connected together and as the piston (not shown) reciprocates in the cylinder 2, the air passes from one end of the said cylinder to the other. Thus there is no obstruction offered to the free reciprocation of the cylinder piston. The dash pots 14 and 16 together with the pistons 17 and 18 attached

thereto prevent the valve 11 from slamming when working toward the seat 10 or away from the same. That is the said dash pot mechanisms act as shock absorbers and cause the said valve 11 to seat or unseat gently. It being understood that under certain conditions, the pressure on each side of the valve 11 may be equalized to such an extent that without the dash pot mechanisms, the said valve would rattle and again, when submitted to sudden pressure, would move with such rapidity as to cause damage when brought to a sudden stop. The small ports located in the valve stem pistons are adapted to admit the steam to the dash pot in the live steam end of the valve. Thus it will require a slight excess of pressure against the cylinder surface or end of the valve to move it from its seat. Therefore, it will not leave its seat under the conditions above mentioned. Again when the valve is opened, the pressure is admitted to the opposite end of the dash pot at which time it will require an excessive pressure on the live steam end to close the valve. This will to a great extent prevent the slamming of the valve when the engine is drifting and at the same time, will not destroy the cushion of the valve in the dash pots.

Having described my invention, what I claim as new and desire to secure by Letters Patent is:—

In combination with a cylinder having a movable piston, a valve adapted to equalize the pressure on both sides of said piston, said valve consisting of a casing having a valve seat, a valve adapted to engage said seat, said valve having on its opposite faces extending stems, pistons located at the ends of said valve stems, recesses formed in the casing and receiving said pistons and adapted to operate as dash pots, said pistons having ports which extend from the piston sides to the faces thereof.

In testimony that I claim the foregoing as my own, I have hereto affixed my signature in the presence of two witnesses:

WILLIAM LESLIE WILSON.
